UNITED STATES PATENT OFFICE

146,364

DESIGN FOR A COMBINED MIRROR AND STAND

Elias A. Kalil, New York, N. Y.

Application August 31, 1945, Serial No. 121,774

Term of patent 3½ years

(Cl. 86—10)

To all whom it may concern:

Be it known that I, Elias A. Kalil, a citizen of the United States of America, residing in New York city, county of New York, and State of New York, have invented a new, original, and ornamental Design for a Combined Mirror and Stand, of which the following is a specification, reference being had to the accompanying drawing, forming part thereof, wherein

The rear of the combined mirror and stand is substantially the same in appearance as the front.

I claim:

The ornamental design for a combined mirror and stand, as shown and described.

ELIAS A. KALIL.
